UNITED STATES PATENT OFFICE

HOWARD B. SCOTT AND RALPH E. MCCOY, OF DAYTON, OHIO, ASSIGNORS TO THE NATIONAL CASH REGISTER COMPANY, OF DAYTON, OHIO, A CORPORATION OF MARYLAND

QUENCHING MACHINE

Application filed February 6, 1930. Serial No. 426,391.

This invention relates to quenching machines, and more particularly to those machines exerting pressure upon an article being cooled.

5 The principal object of this invention is to provide a quenching machine that will properly harden an article placed therein, and one that will prevent practically all the distortion usually occurring during such an operation.

10 Another object of this invention is to free the perforations and the exposed faces of the plates, used herein, from all excess fluid as soon as a quenching operation is finished, to prevent premature cooling and the resulting 15 production of soft spots in the next heated article placed therein.

A further object of this invention is to provide a wiping means, to automatically push the hardened articles from the machine at the 20 end of each operation.

A still further object of this invention is to provide a machine capable of receiving heated articles as fast as they can be fed by an operator.

25 With these and incidental objects in view, the invention includes certain novel features of construction and combination of parts, the essential elements of which are set forth in appended claims and a preferred form or 30 embodiment of which is hereinafter described with reference to the drawings which accompany and form part of this specification.

Of said drawings

35 Fig. 1 is a perspective view of the machine.

Figs. 2a and 2b together show a side elevation of the machine, with many parts in section.

Fig. 3 is a sectional side elevation of the 40 suction device for the upper plate.

Fig. 4 is a plan view on the line 4—4 in Fig. 2a.

Fig. 5 is a side elevation, with parts in section, showing the operating mechanism for 45 the wiping device.

Fig. 6 is a detail plan view of parts shown in Fig. 5.

Fig. 7 is a front elevation of the operating 50 valve and treadle, with parts of the valve shown in section.

Fig. 8 is a plan view of the parts shown in Fig. 7.

Fig. 9 is a diagrammatic view showing the piping for the compressed air and quenching fluid. 55

Fig. 10 is a perspective view showing in detail a portion of the face of a holding plate.

General description

Described in general terms, the machine has 60 two article receiving assemblies, propelled in their operation by compressed air, which is controlled by a treadle valve at the base of the machine. The operation of these assemblies is co-ordinated so that when one assembly is 65 performing a quenching operation, the other is returning to its idle position, preparatory to receiving another article.

The article to be hardened is placed on the face of the lower one of two holding 70 plates. The treadle is then operated, allowing the compressed air to force an upper plate down upon the article, and to force, then, both the article and the plates down an additional distance, so that the article 75 lies well within the confines of a basin. Valves are automatically opened when the plates reach their lowered position, allowing a quenching fluid to be forced through perforations in the plates, which cools the 80 article held between them.

The plates are then opened by the treadle being swung back to its initial position, and a wiping device travels across the face of the lower plate, pushing the hardened article 85 into a suitable receiving vessel.

DETAILED DESCRIPTION

The press assembly

A base 30 (Figs. 1 and 2b) supports a 90 standard 31, on which is fastened a bracket 32 having a sleeve portion 33. Inside this sleeve portion, there is fitted a bushing 34, held in place by a collar 35 at its upper end, and by a lock nut 36 at its lower end. The 95 collar 35 is secured to the sleeve portion 33 by screws 37. A tube 40 is mounted in the bushing 34 for sliding movement, the extent of which is limited, in the upward direction, by its shoulder 41 striking the collar 35.

A bowl-shaped bracket 42 is formed integrally with the upper end of the tube 40, and carries the plate 43, of the pair of companion holding plates 43, 44. The plate rests on the rim 45 of the bracket 42, and is secured thereto by screws 46. This assembly is held in its upper position by springs 47, resting in recesses 50 in the bracket 32, and bearing against the under side of the bowl-shaped bracket 42. Rods 51, secured to under side of the bracket 42, pass through the springs 47 to guide them during their contracting movement. The lower portions of these springs are also guided by the walls of the recesses 50.

A valve pipe 52 is slidably mounted in the tube 40 and in the lock nut 36, and is provided with a collar 53 rigidly secured thereto by set screws 54. A spring 55, resting at its lower end on the lock nut 36, and at its upper end on the bottom of the collar 53, normally holds the pipe 52 in its upper position, as shown in Fig. 2b, where its upper end forms a seat for the stationary valve 56. The valve 56 is held in proper alignment with the valve pipe 52, by the guide fins 57, on its upper end, fitting the inside of the pipe, and is supported by a valve stem 60 rigidly secured to the web portion 61 of the nipple 62. A union 63 connects the nipple 62 with the pipe line 64, Figs. 2b and 9, through which is conducted a quenching fluid.

An air cylinder 65, is rigidly secured to the standard 31 by a bracket 68, and carries a piston 67 fixed to the hollow shaft 70. The piston 67 is driven up and down by compressed air fed to the cylinder 65 through the pipe lines 71, 72 (Figs. 2b and 9), and its movement is limited in each direction by the cylinder heads 73. The lower end of the hollow shaft 70 carries a bowl-shaped bracket 74, similar to the bracket 42, and has secured thereto, the plate 44, identical with plate 43.

A pipe 75 lies inside the hollow shaft 70, and has fastened to its lower end a valve 76, which normally rests on the valve seat 77, fastened in the bracket 74. Near its lower end, the pipe 75 has two slots 80 through which passes a rod 81 secured at both ends in the hollow shaft 70. Depending perpendicularly from the rod 81 is another rod 82, acting as a guide for a spring 83 coiled around it. The spring 83 rests at its lower end on the valve 76, and at its upper end on the under side of the rod 81, and serves to normally keep the valve 76 in its lower or closed position, as shown in Fig. 2b. The mechanism thus far mentioned, constitutes a press assembly, of which there are two on the machine, as shown in Fig. 1.

Control for press assemblies

The control for the operation of these press assemblies, is a valve 84, Figs. 2b, 6 and 7, reciprocated from one position to the other

by arms 85, 86 extending upwardly from the treadle 87 having two operating pedals 90, 91, and fulcrumed on the rod 92 which is supported in the standard 93 rising from the base 30 of the machine. The extent of movement of this treadle assembly is limited by two set screws 94, fastened in the base 30, and lying under the treadle 87.

The valve 84 controls the flow of compressed air to the cylinders 65, 66. When the valve is in the position shown in Fig. 7, air enters through the intake 95, passes through the small openings in the bushing 96 to the chamber 97 formed by the reduction in diameter of the valve 84, and passes out through the opening 100, Figs. 8 and 9, to the pipe line 72, Fig. 9, which connects with the upper opening in cylinder 66 and the lower opening in cylinder 65. This forces one piston 67 to the top of cylinder 65 and the other piston to the bottom of cylinder 66, opening one pair of plates 43, 44, and closing the other pair. The air that was present above the piston in cylinder 65 and below the piston in cylinder 66, from the preceding operation, is allowed to escape through the pipe line 71, into the valve chamber through the opening 101, then through small openings in the bushing 96 to the chamber 102 formed by the reduction in diameter of the valve 84, and then out of the chamber through the gap 103 between the bushing 96 and the large end of the valve 84.

When the treadle 87 is again operated by depression of pedal 90, the valve 84 is moved to its opposite position, as shown in Fig. 9, and the operation of the pistons is reversed, closing plates 43, 44 below cylinder 65 and opening plates 43, 44 below cylinder 66.

Operation of press assemblies

Referring again to Fig. 2, when the piston 67 is lowered, in the manner just described, it lowers plate 44 until the plate lies entirely within the basin 104 extending around the lower plate assembly. Before it reaches this lower position, however, it comes into contact with the article 105, placed on the machine, to be hardened, and then the continued downward movement of the piston 67 presses the lower plate 43 downwardly compressing springs 47, and lowering the tube 40.

A vent 108, leading into channel 136, is provided to allow the escape of stray fluid which might be present in the chamber 109 when the tube is thus lowered. Near the end of this downward movement, the tube 40 strikes the collar 53, and an overhanging cap 106 fastened to the pipe 75, strikes an adjustable stop 107 mounted on the upper cylinder head 73.

From this position, continued movement of the piston 67 moves the hollow shaft 70 relative to pipe 75, the latter being held against movement by the stop 107, moving the valve seat 77 away from the valve 76, compressing

spring 83, and moving the rod 81 from one end to the other of the slots 80. This continued movement also forces the collar 53 and the valve pipe 52 downwardly, against the force of spring 55, leaving the stationary valve 56 standing away from its seat.

The valves 56 and 76 being open, allow fluid to be pumped by the motor 110, Fig. 9, from the reservoir 111, through the pump 112, 10 through the pipe lines 113, 64, 114 and 115, through pipes 52 and 75 into the chambers 116 and 117, and through the perforations 118 in the plates, at which time it comes into contact with the heated article 105, cooling the 15 same. It then runs along the grooves 119 in the plates, and falls into the basin 104, from which it is conducted by the gravity drain 120, into the reservoir 111.

A pressure is maintained in the fluid system at all times by the pump 112, supplemented in its action by the constant pressure tank 121, the amount of pressure being controlled by the variable pressure valve 122. This mechanism for maintaining the fluid 25 pressure, is of the usual construction, and is shown only diagrammatically, since it forms no part of the present invention, except in so far as it forms new combinations with the novel mechanism.

30 The machine remains in this position, with the oil flowing, in the manner just described, until the treadle 87 is reversed, to the position shown in Fig. 7, closing the pair of plates below cylinder 66, at which time the piston 67 in cylinder 65 is raised, by air entering 35 through pipe line 72. This allows the springs 47 to raise the plate 43 to its normal position, allowing the spring 55 to close the valve 56, and allows the spring 83, assisted by 40 gravity, to close the valve 76, stopping the flow of the fluid.

After the flow has stopped, fluid still remains in the chambers 116 and 117, in the perforations in both plates, and in the grooves 45 in the lower plate 43. It is essential that this oil be drawn from the plates, so that a heated article placed on the lower plate, will not be prematurely cooled by lying in the oil remaining thereon, or by having the oil from 50 the upper plate drip down upon it. To overcome this detrimental condition, the machine is provided with suction devices, which will now be described.

55 Suction devices

The suction device in connection with the upper plate, includes a housing 123, Figs. 2b and 3, mounted in an opening, cut in the bracket 74, and has its open end 124 opening 60 into the chamber 117. A beveled edge 125 forms a seat for the valve 126, around the stem 127 of which is a coiled spring 130 pressing against the neck 131 of the housing 123, and against a collar 132, which in turn, 65 presses against a pin 133 extending through

the stem 127 of the valve 126. The spring 130 thus holds the valve 126 firmly against its seat 125 when no pressure is exerted on the upper end of the stem 127. An open neck 134 provides a connection for a suitable suction hose (not shown).

The housing and stem are made such a height that when the piston 67 nears the end of its upward stroke, at the end of an operation, the stem 127 strikes the under side of 70 the bracket 68, and while finishing its stroke, the housing 123 moves relative to the valve 126, now held stationary, opening the latter, and allowing the suction to draw the fluid back out of the perforations 118 in the plate 80 44, preventing any dripping while the plates stand in the open position.

The suction device for drawing the fluid from the lower plate 43 is comprised of a number of apertures 135 cut in the tube 40 85 and the bushing 34, around which is cut a channel 136, in the sleeve portion 33 of the bracket 32, the apertures 135 and the channel 136 being aligned with each other and with a suction pipe 137 when the plates 43 and 44 are 90 open, which allows the suction to draw all the fluid from the channels and perforations in plate 43, and from the chamber 116. However, when the plate 44 forces the plate 43 downwardly in an operation, the apertures 95 135 are moved out of alignment with the channel 136, so that when the valve 56 is opened during the last part of the downward movement, the fluid is prevented from escaping through the suction device. When 100 the plate 44 is raised, the springs 47 raise plate 43 and tube 40 to their normal positions, as shown in Fig. 2b, closing the valve 56 during the first part of the upward movement, and re-aligning the suction groove and apertures during the last part so that the suction 105 may again become effective.

Wiping device

The device employed to wipe the hardened 110 articles off the plates 43 at the end of each operation, will now be described.

A casing 140, Figs. 1, 2b, 4, 5 and 6, secured to the standard 31 acts as a base for the entire wiper assembly. On this casing are 115 mounted two separate wiping units, one working across the face of each plate 43. These two units have the same function, and are identical in every respect, and a description of one will, therefore, suffice for the 120 other.

A rod 141 secured in the casing 140, extends rearwardly, and has fastened at its rear end the cross-rod 142. Mounted in one end of the cross-rod is a guide rod 143, secured at its opposite end in the casing 140, and acting as a guide for the reversing arm 144. This reversing arm 144 has a bearing portion 145 from which a lug 146, (Fig. 5), extends downwardly. To this lug 146 is 130

fastened one end of a rod 147, having on its other end a head 148, which, together with a lock nut, secures the rod to a wiping bar 150. Also fastened to the wiping bar 150, 5 through a boss 149 formed thereon, (Fig. 2b), is the piston rod 151, which carries on its opposite end the piston 152, operating in the cylinder 153, which is securely held in the casing 140. The relative position of the rods 10 147 and 151 is shown in Fig. 4. The piston 152 is operated by compressed air, admitted into the cylinder through ports 154, 155 in the cylinder heads 156, 157.

To control the operation of this wiping device, there is provided a single acting trip arm 160, Figs. 5 and 6. In one end of this trip arm is mounted a latch 161 having a cam face 162, and pressed outwardly by a spring 163, shown in dotted lines. A shaft 164 is 20 mounted for oscillatory movement, in a part of the casing 140, and is fastened at one end to the arm 160 and at the other end to an upwardly extending tappet 165, having a set screw 166 abutting one end of the valve 167. 25 The valve 167 is a duplicate of the valve 84, already described in detail, so further explanation of the same is not necessary.

When the plate 44 descends on its closing stroke, the bracket 74 strikes the cam face 162 30 of the latch 163, and due to the trip arm 160 being held against counter-clockwise movement by the shoulder 170, the bracket 74 cams the latch 161 to the right, as viewed in Fig. 5, against the pressure of the spring 35 163, allowing the bracket 74 to complete its downward stroke without moving the trip arm 160.

When the plate 44 begins its upward stroke, the quenching operation is completed, 40 and the hardened article is ready to be wiped off the plate 43. As the bracket 74 travels upward, it strikes the under side of the latch 161, and while pushing the latch out of its path, it rotates clockwise, the trip arm 160 45 and the tappet 165 carrying the set screw 166, which in turn moves the valve 167 to its right-hand position, as viewed in Fig. 5. As the bracket 74 continues its upward stroke, it moves out of contact with the latch 161, 50 allowing gravity to return the trip arm 160 to its normal position, as shown in Fig. 5.

This shifting of the valve 167 to the right allows compressed air to flow from the intake port 171 through the left side of the valve, 55 as viewed in Fig. 5, in the same manner as was described in connection with the valve 84, and out through the pipe line 172, Fig. 4, which conducts it to the rear end of the cylinder 154, where it enters the cylinder 60 through the port 154, Fig. 2b, in cylinder 157. The air then forces the piston 152 to the forward end of the cylinder, while the air which is in the cylinder ahead of the piston is allowed to escape through the port 155 in 65 the forward cylinder head 156, through the

pipe line 173, Fig. 4, and through the right-hand side of the valve 167, Fig. 5.

The wiper 150, being secured to the forward end of the piston rod 151, is moved across the face of the plate 43, wiping off the hardened article. The rod 147 also being connected to the wiper 150, is moved forward, bringing with it the reversing arm 144. When the piston nears the end of its forward stroke, a set screw 174 in the end of the reversing arm 144 strikes the right-hand end of the valve 167, and moves it to its initial left-hand position, as shown in Fig. 5. The valve being in this position, allows the compressed air to enter its right-hand side, from which it is conducted through the pipe line 173 to the port 155 in the forward end of the cylinder. This forces the piston to the rear of the cylinder, the air in back of the piston escaping through the port 154, pipe line 172, and the left-hand side of the valve 167. When the piston is thus moved to the rear of the cylinder, it pulls the wiper 150 and the reversing arm 144 backward with it, to the position shown in Fig. 2b, completing 90 the operation.

Structure of the holding plates

The holding plates 43, 44, see particularly Fig. 10, have large grooves 119 lying at right angles to each other extending across the entire plate. These grooves form raised surfaces 176 in which are cut the small grooves 177 also running at right angles to each other, and connecting with the large grooves 119. At each intersection of the grooves 119 and 177 there are perforations 118. The perforations all extend through the plates 43, 44 from one side to the other, as shown in Fig. 2b, and allow the passage of the quenching fluid from the chambers 116, 117 to the heated article 105.

The particular form of grooving and perforating shown in Fig. 10, has two outstanding advantages. First, the perforations are placed so close together that cool fluid is directed on practically every part of the article at the same time, and the grooves are so proportioned and arranged that the fluid is readily carried away by them, allowing the flow of cool fluid to continue from the perforations, securing a uniform contraction of the metal, and consequently reducing the amount of distortion. Secondly, the grooves are cut wide enough to leave only the small plateaus 180 of the original plate surface contacting with the heated article. This reduces the premature cooling occurring before the fluid is released and, therefore, secures a more uniform and positive hardening.

While the forms of mechanisms herein shown and described are admirably adapted to fulfill the objects primarily stated, it is to be understood that it is not intended to confine the invention to the forms or embodiment

herein disclosed, for it is susceptible of embodiment in various forms all coming within the scope of the claims which follow.

What is claimed, is:

- 5 1. In a machine of the class described having a plate; means, including a hollow shaft, to guide the plate; a pipe therein adapted to carry a fluid; and means, including a relative movement of the hollow shaft and pipe to begin a flow of the fluid.

10 2. In a machine of the class described having a plate adapted to be moved into contact with an article to be hardened; a hollow shaft to guide the plate in its movement; a pipe in the shaft to carry a fluid; and a valve controlling the flow of the fluid, and operated by a relative movement of the hollow shaft and pipe.

15 3. In a machine of the class described, a perforated plate; a bowl-shaped bracket secured to the back of the plate, creating a pocket behind the plate; means to move the plate; means to cause a passage of fluid into the pocket and through the plate perforations, when the plate is moved; and a suction means to clear the pocket and the perforations of the fluid at the end of an operation.

20 4. In a machine of the class described, a perforated plate; means to pass a fluid through the perforations; and a suction means to clear the perforations of the fluid at the end of an operation.

25 5. In a machine of the class described, a perforated plate; means to pass a fluid through the perforations; a suction means to clear the perforations of the fluid; and means to automatically operate the suction means at the end of a machine operation.

30 6. In a machine of the class described, a perforated plate; a bowl-shaped bracket fastened to the back of the plate; means to pass a fluid through the perforations; and a suction means mounted on the bracket, and adapted to clear the perforations of the fluid, at the end of an operation.

35 7. In a machine of the class described, a mechanism including a plate having perforations; means to guide the plate for reciprocating movement; and a suction device having a valve automatically opened as the mechanism reaches its withdrawn position to create a suction through the perforations.

40 8. In a machine of the class described, two press assemblies operated pneumatically; a valve; means to operate one assembly through its pressing stroke, and the other assembly through its return stroke, when the valve is in one position; and means to reverse the operation when the valve is in another position.

45 9. In a machine of the class described, a bracket; a fluid retaining tube; a stationary valve head closing an end of the retaining tube; means to yieldingly hold the bracket and closed by the valve head, and thus allow a passage of fluid from the tube to the bracket.

50 10. In a machine of the class described, a plate to hold an article to be hardened; large grooves in the plate to lessen the amount of plate surface contacting with an article placed thereon; and smaller grooves to allow a passage of quenching fluid to the first-mentioned grooves.

55 11. In a machine of the class described, a plate to hold an article to be hardened; two series of large grooves, one series lying at an angle to the other, and forming between them, raised surfaces; a perforation in each raised surface; and small grooves connecting the perforations with the large grooves, to allow the passage of a quenching fluid.

60 12. In a machine of the class described, a plate having raised surfaces, formed by the intersecting of large grooves; and small grooves lying within the raised surfaces.

65 13. In a machine of the class described, a plate to hold an article to be hardened; and an automatic wiping means traveling across the face of the plate at the end of each operation, to clear the plate of the article placed thereon.

70 14. In a machine of the class described, a lower plate upon which an article to be hardened is placed; an upper plate assembly; means to lower the upper plate assembly to press the article against the lower plate; and a wiping means, tripped for operation by the upper plate assembly upon its return movement.

75 15. In a machine of the class described, two plate assemblies between which an article to be hardened is placed; means to close and open the assemblies; and a wiping means tripped for operation by one of the assemblies during its opening movement.

80 16. In a machine of the class described, two plate assemblies between which an article to be hardened is placed, a wiping means positioned to clear one of the plates of the article placed thereon; and a valve operated by the other plate assembly to control the action of the wiping means.

85 17. In a machine of the class described, a wiping means having a valve operated by a moving part of the machine; a movable wiper element; and an arm rigid with the wiper element, adapted to return the valve to its original position, when the wiper element reaches its operated position.

90 18. In a machine of the class described, a plate adapted to be lowered into contact with an article to be hardened, a hollow shaft to guide the plate in its movement, a pipe therein adapted to carry a fluid, means to control the flow of the fluid, means to move both the

shaft and pipe in unison, and means to retard the pipe while the shaft continues its travel, to cause the controlling means to operate.

- 5 19. In a machine of the class described, a cylinder, a hollow shaft running therethrough, a piston therein secured to the shaft, a perforated plate on an end of the shaft, the cylinder and piston being used in reciprocating the shaft and plate, and means for causing a flow of a quenching fluid through the shaft and plate.

- 10 20. In a machine of the class described, a perforated plate adapted to be lowered upon an article to be hardened, a hollow shaft extending upwardly therefrom, a piston secured to the shaft, a cylinder in which the piston is situated, and through which the shaft extends, means to cause the piston to move the shaft upwardly and downwardly, and means to cause a flow of quenching fluid through the shaft and plate when the plate is moved to its lowered position.

- 15 21. In a machine of the class described, a perforated plate suspended over an article to be treated, means to lower the plate to contact the article, means to pass a quenching fluid through the perforations, means to check the flow, means to raise the plate, and means to prevent a dripping of the excess fluid from the plate after the flow has been checked and the plate raised.

- 20 22. In a machine of the class described, a plate adapted to contact with an article to be treated, means to pass a quenching fluid upon the article, means to check the flow, and means to remove the residue of fluid from the plate after the flow is checked.

- 25 23. In a machine of the class described, a plate adapted to contact with an article to be treated, means to pass a quenching fluid upon the article, means to check the flow, means to prevent a dripping of the fluid from the plate after the flow is checked, and means to automatically cause operation of the preventing means at the end of a quenching operation.

- 30 24. In a machine of the class described, a plate adapted to hold an article to be treated, a hollow shaft adapted to move with the plate, means to flow a quenching fluid through the shaft and plate, and means to remove the fluid from the plate and shaft after the flow is stopped.

- 35 25. In a machine of the class described, a plate adapted to hold an article to be treated, a hollow shaft adapted to move with the plate, a suction pipe registering with openings in the shaft, and means to lower the plate and shaft, and thus sever the registration between the pipe and the openings.

- 40 26. In a machine of the class described, a perforated plate adapted to hold an article to be treated, means to cause a suction through the perforations, and means to auto-

5 matically check the suction when the plate is lowered.

- 45 27. In a machine of the class described, a wiping attachment for a quenching machine, including a reciprocating wiping element, a member moving therewith, and means, moved to one position during the operation of the quenching apparatus, to cause movement of the wiping element in one direction, and moved to another position by the member to cause a return movement of the wiping element.

In testimony whereof we affix our signatures.

HOWARD B. SCOTT. 80
RALPH E. McCOY.
